CUTTER CHAIN STRUCTURE

Robert F. Prox, Jr., West Terre Haute, and Benjamin F. Woods, Terre Haute, Ind., assignors to Frank Prox Company, Inc., Terre Haute, Ind., a corporation

Application June 6, 1951, Serial No. 230,176

3 Claims. (Cl. 74—254)

1

This invention relates to a cutter chain structure, particularly employed in coal mining, but which is equally applicable to other uses.

The invention pertains to the interlocking of the main pins in their respective connecting links from which the chain is formed. In cutter chains of this character it is desirable that the chain be capable of disassembling in case of breakage or replacement of broken parts with a minimum loss of time, particularly when being used in mines. At the same time it is essential that the links be interlocked to prevent separation of the links when in operation.

This invention, therefore, is particularly directed to the provision of a groove formed in the main pin connecting the links for interlocking reception of a locking rivet mounted to extend through suitable transverse bores in the connecting link tangentially of the respective main pins to interlock with the groove therein and prevent axial displacement thereof, and wherein the rivets are securely held in place, but capable of being hammered free of the pin for removal thereof.

The full nature of the invention will be understood from the accompanying drawings and the following description and claims:

Fig. 1 is a central vertical section through a connecting link and adjoining bit carrier link with the bit block in elevation.

Fig. 2 is a top plan view of a disassembled connecting link with one of the main pins mounted therein.

Fig. 3 is a perspective view of a main pin.

In the drawings there is shown a cutting chain structure comprising a connecting link 10 and an adjoining bit carrying link 11 comprising the side plates 12 adapted to embrace the respective ends of the connecting link. Said bit carrying link also includes an upstanding bit block 13 carrying a removable bit 14 secured in place by a set screw 15.

The connecting link is provided with the usual pin receiving openings 16 extending transversely through opposite ends thereof in which an annular bushing 17 is mounted, the bit carrying link having its side plates 12 provided with openings mating and registering with said bushings. The connecting link 10 is adapted to provide a pivotal connection between adjacent bit carrying links in the usual manner, the pivotal connections therebetween comprising the main pins 18 adapted to be inserted transversely through the openings 16.

Extending from top to bottom of each con-

2

necting link adjacent the inner side of each of the openings 16 there is provided a rivet bore 19 for receiving a locking rivet 20. The said bores and locking rivets are centrally disposed in the connecting link generally tangential of the respective openings 16 and the bushings 17 secured therein with approximately half of the diameter thereof traversing the openings. As illustrated in Fig. 1, said bores intercept the inner surfaces 10 of the bushings, extending through adjacent side walls thereof.

Each of the main pins 18 is formed with a groove 21 shown herein as annular, but which may extend only partially around one side of the pin, and which is preferably semi-circular in cross section to conform with, receive and seat therein a locking rivet 20 when inserted through the bore 19. Thus, with the main pins mounted to pivotally connect the links they are locked 20 against axial displacement or removal by their respective locking rivets 20. For securing rivets 20 in locking position, they are each provided with a flanged head 22 adapted to engage and seat within a countersink 23 formed in the connecting link at one end of the bore 19. The other end of the bore terminates in a corresponding countersink 24. When the locking rivet is inserted through the bore into locking engagement with the main pin, it has a free end indicated by 25 dotted lines at 25. Such free end of the pin, however, is capable of being peened over into a flanged head 26 by hammering, the metal of which the rivet is formed being sufficiently soft for this purpose. With the free end peened over, 30 the rivet will be restrained from longitudinal or axial displacement for locking the main pin in position while permitting free oscillation or rotation thereof within the bushing 17. In this connection it is noted that the main pin has one end 35 thereof broached to provide flats 27 adapted to mate with a corresponding flat formed in the pin receiving opening of one of the side plates 12.

This structure is such that the main pins will 40 be locked against removal by the locking rivets. But when it is desired to disassemble the chains on the job for repair or replacement, the relatively soft metal locking rivets may be readily knocked out of their locking engagement by hammering the peened over end with sufficient force 45 to displace it. With the locking rivet forced free of interlocking engagement with the main pin, said pin may be then readily removed. The chain 50 can then be reassembled merely by re-inserting the main pin and forcing the locking rivet back

in place, or inserting a new locking rivet, and again peening over its free end in place.

The invention claimed is:

1. A cutting chain structure comprising alternate connecting links and bit carrying links having side plates embracing adjacent ends of the connecting links with aligned openings in the connecting ends of the respective links, bushings mounted in the openings of the connecting links having an internal diameter registering with the internal diameter of the mating openings in the bit carrying links, said latter openings having opposed flats, said connecting links each having a pair of bores extending transversely and tangentially of the openings therein in intercepting relation with the inner surface of said bushings and on adjacent sides thereof, a main pin having a centrally disposed groove receivable within each of said bushings to extend through the mating openings in said bit carrying link with said groove in mating relation with the adjacent said bore, a locking rivet extending through each of said bores with a portion thereof tangentially seating in the groove of said pin to interlock and prevent axial displacement thereof, and means for removably securing each of said locking rivets in pin locking position.

2. A cutting chain structure comprising alternate connecting links and bit carrying links having side plates embracing adjacent ends of the connecting links with aligned openings in the connecting ends of the respective links, bushings mounted in the openings of the connecting links having an internal diameter registering with the internal diameter of the mating openings in the bit carrying links, said latter openings having opposed flats, said connecting links each having a pair of bores extending transversely and tangentially of the openings therein in intercepting relation with the inner surface of said bushings and on adjacent sides thereof, a main pin having a centrally disposed groove receivable within each of said bushings

5 to extend through the mating openings in said bit carrying link with said groove in mating relation with the adjacent said bore, a locking rivet extending through each of said bores with a portion thereof tangentially seating in the groove of said pin to interlock and prevent axial displacement thereof, and means for removably securing each of said locking rivets in pin locking position.

10 3. A cutting chain structure comprising alternate connecting links and bit carrying links having side plates embracing adjacent ends of the connecting links with aligned openings in the connecting ends of the respective links, said connecting links each having a pair of bores extending transversely and tangentially of the openings therein in intercepting relation with the inner surface of adjacent sides thereof, a main pin having a centrally disposed annular groove receivable within each of the mating openings 15 of the respective links for pivotally connecting their adjacent ends and with said groove in mating relation with an adjacent bore, a locking rivet extending through each of said bores with a portion thereof tangentially seating in the groove of said pin to interlock and prevent axial displacement thereof, and means for securing each of said locking rivets in pin locking position 20 through opposed countersunk pin head engagement with opposed sides of said link, one of the heads of said pin being deformable to permit forcible removal thereof from its interlocking engagement with said main pin.
